UNITED STATES PATENT OFFICE

2,021,634

CURTAIN ROD

Benedict E. Moriarty, Kenosha, Wis.

Application August 11, 1934, Serial No. 739,458

2 Claims. (Cl. 156—19)

This invention appertains to curtain rods and has for one of its primary objects to provide a rod in which the use of supplemental detachable supporting brackets is entirely dispensed with,

5 whereby easy attachment of the rod to the window casing is assured with a minimum amount of damage to the casing.

Another important object of the invention is to provide a curtain rod having inwardly directed 10 attaching feet formed on its terminals with the feet extending below the rod for facial abutment with the window casing and having keyhole slots therein in alinement with the body portion of the rod for receiving headed fastening elements 15 anchored in the window casing, the arrangement of the keyhole slots and feet assuring the sturdy supporting of the rod without tilting under the weight of the curtain.

A further salient object of my invention is to 20 provide novel means for constructing the rod whereby the same will be effectively braced at the curved portions thereof, which are normally subjected to the greatest strain.

A still further object of my invention is to 25 provide an improved curtain rod, which will be durable and efficient in use, one that will be simple and easy to manufacture and one which can be placed upon the market at a reasonable cost.

With these and other objects in view, the invention consists in the novel construction, arrangement and formation of parts, as will be hereinafter more specifically described, claimed and illustrated in the accompanying drawing, in which:—

35 Figure 1 is a fragmentary rear elevation of my improved curtain rod.

Figure 2 is a transverse section through the body portion of the rod looking in the direction of the arrows.

40 Figure 3 is a detail section through the rod taken on the line 3—3 of Figure 2 looking in the direction of the arrows.

Figure 4 is a fragmentary top plan view of the curtain rod.

45 Referring to the drawing in detail, wherein similar reference characters designate the corresponding parts throughout the several views, the letter A generally indicates my improved curtain rod which can be of the telescopic construction and as shown, the same embodies an end section 5 having adjustable engagement with a similar end section or adjustable center section 6.

The end section 5 embodies a longitudinally extending straight body portion 7 and a rearwardly directed curved right-angularly position

supporting arm portion 8. The upper and lower edges of the longitudinal portion 7 of the section 5 are in-turned as at 9 to provide guideways for receiving the section 6.

In connection with the end section 5, I utilize 5 an attaching foot 10. This foot is disposed in a vertical plane and can be provided with a struck-out reinforcing rib 11. Formed integral with one side edge of the foot 10 is the forwardly projecting leg 12, which is of less width than the width 10 of the section 5. The outer end of the leg 12 is provided with an inwardly curved extension 13 and the foot with its curved extension conforms to the configuration of the arm 8 and the body 7 of the end section 5. This leg 12 and its extension 15 13 is provided with a raised centrally disposed rib portion 14 and laterally extending flanges 15. The upper and lower edges of the body 7 and the arm 8 are provided with in-turned beads 16 which snugly engage the flanges 15 and hold the 20 leg and its extension firmly in position. As shown, the in-turned extensions 16 engage the central rib 14 and thus, hold the leg against lateral movement.

Directly above the reinforcing rib 11 on the foot 25 10 is a keyhole slot 17 and this slot is in alinement with the body portion of the rod.

In use of my improved curtain rod, a headed fastening element, such as a flat nail or screw, is anchored in the casing the head of which is 30 placed within the keyhole slot. As the foot depends below the keyhole slot, the same forms an effective brace or bracket for supporting the rod. As the fastening element is in alinement with the body portion of the rod, the maximum amount 35 of the weight is supported by the fastening element.

By having the arcuate extension 13 on the leg 12, the end section 5 is thoroughly braced at its curved portion which prevents the twisting of the 40 rod when the same is in use. Further, the method of uniting the section 5 with the leg 12 insures a strong and sturdy joint.

While I have shown the foot 10 depending below the rod, it is to be understood that the same 45 can extend above the rod instead of below, if such should be desired.

From the foregoing description, it can be seen that I have provided an exceptionally simple and durable curtain rod in which extraneous supporting brackets are eliminated.

Changes in details may be made without departing from the spirit or the scope of this invention, but what I claim as new is:—

1. A curtain rod comprising an end section in- 55

- cluding a longitudinally extending portion and a rearwardly directed arm, a supporting leg fitted against said arm and having a curved extension engaging the longitudinal portion of the end section, in-turned flanges on the upper and lower edges of the section engaging the leg and its extension, a depending foot formed on the leg having a keyhole slot therein in alignment with said leg.
- 10 2. A curtain rod comprising an end section having a longitudinally extending body portion

and a rearwardly directed arm, a leg fitted against one face of the arm having a curved extension engaging the body portion, said leg and extension being provided with a centrally disposed rib and lateral flanges, in-turned beads formed on a portion of the body portion and on the arm of said end section engaging the flanges and abutting the rib, and a depending foot formed on the rear end of said leg.

10
